(57) **CLAIM**

The ornamental design for a railing for a marine vessel as shown and described.

DESCRIPTIONFIG. 1 is a front perspective view of a railing for a marine vessel, the railing being shown mounted on a pontoon boat; FIG. 2 is an isolated front perspective view thereof; FIG. 3 is an isolated rear perspective view thereof; and, FIG. 4 is a side elevation view thereof.
The broken lines in the drawings illustrate portions of the railing for a marine vessel and pontoon boat that form no part of the claimed design.**1 Claim, 4 Drawing Sheets**# US D1,066,208 S
